3 Claims. (CL 274—10)

This invention relates to a phonograph of the type capable of playing automatically and continuously a large number of records one by one.

The object of this invention is to provide a phonograph which is capable of serving for either a double sided and single-sided records by mere displacement of a cam group particularly arranged.

A further object of this invention is to provide such a phonograph as is able to play a large number of records one by one irrespective of their different dimensions.

According to this invention, a large number of large and small records supported on a record hanging device which is arranged at one side of a supporting plate, may be fetched one by one and put on the turn table and then the record, in the case of a single-sided record after it has been played as well as in the case of a double-sided record after it has been once turned over and played, may be removed from the turn table to suspend on a record hanging device arranged at the opposite side of the supporting plate and at the same time a new record may be fetched and treated in the same manner, all records being played one in a quite same way as another.

Accompanying drawings show the case of the phonograph being served for a double-sided record and the condition in which a record, after it has been played on one side thereof and turned over, may be put on the turn table and the pick-up is about to start towards said record.

Fig. 1 is a plan view of the phonograph according to the invention in which the record is removed and the turn table is partly destroyed to show clearly the starting switch and record fetching device.

Fig. 2 is a rear side view of the phonograph seen from the side shown by arrow II in Fig. 1.

Fig. 3 is an elevation seen from the side shown by arrow III in Fig. 1.

Fig. 4 is a side view seen from the side shown by arrow IV in Fig. 1.

Fig. 5 is another side view seen from the side shown by arrow V in Fig. 1.

Fig. 6 is a side view of the record fetching device and cam group.

Fig. 7 is a plan view of the mechanism for controlling the position of the pick-up.

Fig. 8 is a side view of the mechanism shown in Fig. 7.

Fig. 9 is a vertical section through the shaft of a record holding member.

Fig. 10 is a sectional view of the record fetching device and its driving cam on a larger scale.

Record hanging devices (refer to Figs. 1 and 2)

The device is composed of two upright rods 5 and 3 arranged respectively at opposite sides on the supporting plate 1. The rod 2 for unplayed records R is provided with a cross rod 4 having a hook at its end. On said cross rod is slidably mounted a disc 6 which is pressed at 10 its rear side by a spring 5 wound on said cross rod 4. The rod 3 for played records S is provided with a cross rod 7 which is slightly bent upwards near the central part.

Starting switch (refer to Figs. 1 and 2) 15

The starting switch for driving the starting motor adapted to impart proper movements to every mechanism at the end of playing (the turn table is always in rotation by means of other motor 9') is composed of a plate 10 secured on the supporting plate 1 in the space between the plate 1 and the turn table 9. On one side of said plate 10 is fixed a metal piece 11 which is connected through the conductor to an electric source and the motor 27, and on the other side of the plate 10 is pivoted an elbow lever 12 having a slot 23 on one arm and a projecting piece 24 on another arm. Said plate 10 is further provided with a separate elbow lever 14 pivoted at 13 which is provided at one end with a projection 15 and a guiding member 17 and at the other end with a flange 16 which is connected at the end to the plate 10 by means of a spring 22. A sliding piece 18, which is connected at 35 the bent end thereof to a spring 19 secured on the lever 14, is slidably arranged in the guiding member 17. On one side of the plate 10 is pivoted at 20 a lever 21 which is adapted to come into touch with a small projection (not shown) 40 provided under the sliding piece 18.

As the elbow lever 12 is moved in the direction shown by the arrow with the movement of the pick-up during the playing of a record the end thereof may be freed from the flange 16 of 45 the lever 14, the free end of the sliding piece 18, on account of one end of the lever 14 being drawn from the spring 22, may be engaged with a small upright piece 25 fixed to the plate 10 so as to prevent the movement of the lever 14. 50 However, the projecting piece 24 of the lever 12 may be still moved along the upper toothed face of the sliding piece 18. The projection 26 of the lever 21, after the needle has passed over the end of the sound groove, may be pushed 55

outward by the arm of the lever 12, so that the sliding piece 18 also may be pushed back against the spring 19 to get free from the engagement with the upright piece 25, whereupon the metal pieces 11 are pressed by the projection 15 to come into contact with each other as the result of the lever 14 being further drawn by the spring 22. Thus, the circuit is to be instantaneously closed to start the motor 27 mounted on the back side of the supporting plate 1. The teeth provided on the sliding piece 18 are so arranged as not to prevent the movement of the projecting pieces 24 in the direction towards the center of the turn table but to engage with the piece 24 in the case of the latter moving in opposite direction.

Mechanism for driving the pick-up (refer to Figs. 2, 5, 7 and 8)

20 The pick-up 28 is movably mounted by means of a ball bearing on the base 105 fixed to the supporting plate 1 and is supported to move towards and away from the record on the turn table by means of a supporting rod 29, which 25 passes through the slot 30 of the plate 1 and screwed on the lever 31 under the plate 1. Said lever 31 is mounted loosely on a shaft 34 passing through both the frame 32 and a tray-form cam disc 33 fixed on the frame. The shaft 34 is provided at the lower end thereof with a lateral projection 35. Between the disc 33 and the hub of the lever 31 is interposed a ring 36, on the opposite sides of which two rollers 37 are rotatably arranged. The tray-form cam disc 33 is provided with two recesses 38 at the opposite parts on the upper rim thereof. The lateral projection 35 may always be pressed against the tray-form cam disc 41 by the action of a spring 47 fixed to the projection of the ring 36 and 40 the frame 32. The tray-form cam disc 41 is provided with two recesses 40 at the opposite parts on the upper rim and is mounted on the driving shaft at one end thereof. In the course of playing of a record said projection 35 rests 45 in one of said recesses 40. The moment the playing of a record has finished and the circuit has been closed, as stated above, to start the motor 27, the driving shaft 39 and the disc 41 are rotated in the direction shown by arrow in 50 Fig. 8 through a shaft 42, pinion 43 and toothed wheel 44 (refer to Fig. 2) and at the same time the disc 101, which is provided with two recesses 101' at opposite parts on the periphery thereof, and is mounted on another end of the shaft 39, 55 is rotated in the direction shown by arrow in Fig. 2, and in consequence the roller 103 of the switch 102, which fits in one of the recesses 101', during the playing, comes out of the recesses 101' to roll on the periphery of the disc 101, 60 whereupon the switch may be instantaneously closed to run the motor continuously till the roller 103 will fit in the next recess.

On the other hand, the lateral projection 35, which is fitted in one of the recesses 40, may be 65 gradually turned outwards by the rotation of the tray-form cam disc 41 to rotate the shaft 34 to certain extent, so that the roller 37 of the ring 36, which is fitted in one of the recesses 38 during the playing, may be rolled on the rim 70 of the tray-form cam disc 33. Consequently the lever 31, then pick-up 28 may be raised to separate the needle from the surface of the record and at the same time be carried away outside the record as the result of the stop 46 provided 75 on the back side of the hub of the lever 31 being

pushed by the radially projecting rib 45 provided on the back side of the ring 36 fixed to the shaft 34, said rib 45 extending axially over the upper face of said ring 36.

Mechanism for turning over and removing the record (refer to Figs. 1, 2, 3, 4 and 5)

A device for turning over and removing a record is composed of two bent bars 49 which lie on the plate 1 outside the turn table 9, the fore end of each bar being provided with a rotatable holding member 48 having a longitudinal groove in which the periphery of a record may be fitted, while the rear end thereof is bent to pass through openings of the plate 1, the groove of the block 52, which is fixed on each end of a shaft 51 journalled in bearings 50 (refer to Fig. 3), and each curved fork 55, which is fixed on the outer end of each shaft 54 journalled in bearings 53. On one of said bars 49 may be slidably mounted a bent rod 58 which is provided at fore end with the teeth adapted to engage with the toothed wheel 56 loosely mounted on the shaft 48' of the holding member 48 and at the rear end with a ball 57 adapted to cooperate with the abutment 57' on the plate 1. The holding member 48 is caused to rotate in a determined direction only through the cooperation of a pinion 60 fixed to the shaft 48' of said member 48 and pawl 59 pivoted on the toothed wheel 56. To 20 keep the holding member 48 in horizontal position at every rotation thereof through 180°, the strong springs 61 are provided on each bar 49 in such a manner that the free ends thereof may be pressedly fitted in one of the grooves 48'' transversely provided on the upper and lower sides of the shaft 48' of the holding member (Fig. 9). The inner end of each shaft 54 may be brought into contact with the outer end of each arm 64 which is pivoted to the head of a shaft 63 journalled in a bearing 62 and is connected at the inner side to each other by a spring 65.

The driving levers 67 and 68, which are supported pivotally in a supporting member 69 (refer to Fig. 3) and are adapted to drive the device for turning over and removing the record, are caused to come in touch at one end respectively with the underside of the shaft 63 and of the piece 66 fixed to the shaft 51. The other 45 ends of each lever 67, 68 are respectively positioned under the corresponding cam discs in the cam group slidably mounted on the driving shaft 39 which is journalled in bearing 70 (refer to Fig. 5). The spring 68' attached to the lever 68 (refer to Fig. 3) partly counterpoises the 50 over-weight of the left arm of lever 68 to facilitate the operation of the cams. Said cam group is composed of six cam discs A, A', B, B', C, C'. This cam group is mounted on the shaft 39 by 55 inserting the pins 72 projecting from the side thereof into the holes in the flange of the sleeve fixed to the driving shaft in such a manner that the cam group is able not only to rotate together with the shaft 39 in the direction shown 60 by arrow, but also to slide on said shaft by the lever 74 pivoted to the supporting member 73 (refer to Fig. 6). Said lever 74 may be connected through the link 75 to the arm 76 secured to the lower end of the shaft of a control 65 handle 77 on the supporting plate 1. This handle may be used for controlling the machine to be adapted for either of the double-sided and single-sided records. For this purpose the handle is provided with a pointer which moves over 70 75

a scale having the mark D for the double-sided record and the mark 0 for the single-sided record. In Fig. 1 the pointer points to the mark D.

The cam discs A, B and C are all used for the double-sided record and are adapted to engage respectively with the lever 68, lever 67 and the record fetching device (explained hereinafter). On the contrary the cam discs A', B' and C' are all used for the single-sided record and are adapted to engage respectively with the lever 68, 67 and the record fetching device in the case of the cam group being displaced by the handle 77. The cam discs A and A' are nearly similar in form (refer to Figs. 3 and 6) but only a point 2A of the disc A is slightly cut off, that is to say, the distance from the centre of the cam disc A to the point 2A is a little shorter than that to the opposite point 1A. In the event of the lever 68 being pressed by the point 1A of said cam disc A the record-turning-over-and-removing device may be driven to remove the record from the turn table, while in the case of the opposite point 2A said device may be driven to turn over the record. If the machine is used for the single-sided record the lever 68 is to be engaged with the cam disc A'. In this case, both points 1A', 2A' of the cam disc A' are at an equal distance from the centre, so that the cam disc A' may be used always to remove the record from the turn table. The cam discs B and B' are mainly similar in shape and contain respectively cam faces 1B, 2B, 3B, 4B and 1B', 2B', 3B', 4B' but the former is partly larger than the latter by the part containing the point 4B. In the event of the lever 67 being pressed by either the point 1B or 3B of the cam disc B the record-turning-over-and-removing device may be driven to hold the record, while in the case of the lever 67 leaving either the point 2B or 4B said device may be driven to set free the record thus held.

When the machine may be used for the single-sided record, the lever 67 is to be engaged with the cam disc B'. In this case both points 1B', 3B' are adapted to hold the record, while the points 2B', 4B' serve to set free the record. The cam discs C and C' may be used for driving the record-fetching-and-putting-on device. The cam disc C coincides in size and shape with each half of the cam disc C'. In the event of the machine being used for the double-sided record, said device may be raised up by engagement of the curved part thereof with the point 1C of the cam disc C and pushed upwards with the point 3C to fetch the unplayed record hanging on the rod 2. In the case of the single-sided record being played, said device may be raised up with both points 1C' and 4C' of the cam disc C' (refer to Fig. 6) and be pushed upwards with the points 3C' and 6C' to fetch the unplayed record. Each set of the cam discs, A, A', B, B' and C, C' is mounted on the driving shaft 39 at such an angle that the parts of the cams in each set which are of similar shape may be in line with each other and each cam may drive the corresponding member at proper time in relation to each other. The cam group may not be rotated during the playing but the moment the switch has been closed, it may be rotated together with the shaft 39. If the back side of a double-sided record, which has been turned over and put on the turn table as shown in the drawings, will be completely played and the pick-up is carried away outside the record, the lever 67 may be pressed at one end thereof by the

point 1B of the cam disc B (refer to Fig. 3), as the result of which the shaft 63 may be pushed up by the other end of the lever 67. At the same time the record-turning-over-and-removing device may be driven to hold the played record with the holding member 48 by the action of arms 64, shaft 54 and curved forks 55. The lever 68, later on, may be pressed with the cam disc A, and in consequence the aforesaid device may be gradually raised up in accordance with the rotation of the shaft 51 resulting from the movement of the piece 66, accompanied by the rotating record, which is rotated by the cooperation of the ball 57 of the bent rod 58 and the abutment 57' as well as by the cooperation of the teeth provided at the fore end of the rod 58 and toothed wheel 56, and then the device puts up the record on the cross rod 7 of the record hanging device 3 in the case of the lever being pressed with the point 1A of the cam A. At the same time the point 2B of the cam B is adapted to leave the lever 67, so that the holding members 48 may be opened to free the record from holding, thereafter the record-turning-over-and-removing device may gradually return to the original condition.

When the back side of a double-sided record will be played, that is to say, the record will be only turned over, the record-turning-over-and-removing device may be driven to hold the record as the result of the lever 67 being pressed by the point 3B of the cam B and simultaneously therewith may be raised up gradually due to the engagement of the lever 68 with the point 2A of the cam disc A. However the distance from the center to the point 2A of the cam disc A is smaller than that to the point 1A and also the cam face between the points 3B and 4B is of equal radius, so that said device may be driven to fall down gradually with the record turned over to put it on the turn table, whereupon the record, after it has been put on the turn table, may be freed from the device simultaneously with the lever 67 leaving the point 4B of the cam disc B. The drawings show the condition of the machine at this moment. (In some figures of drawings the record is removed to bring out the mechanism clearly.)

Mechanism for fetching and putting-on the records (refer to Figs. 1, 2, 5 and 6)

The record-fetching-and-putting-on device is composed of a curved part 78 extending downwards through the plate 1 and an arc-formed part 79 which is formed integral with the former part and partly encloses the turn table. Said device is pivoted with the spindle 81 in the grooved support 80 mounted on the plate 1. The enlarged part, that is to say, the base part of the arc-formed part is provided with two sets of openings 82 and 83 (refer to Figs. 1 and 6). At the back side of said part two bent levers 86 are fixed on the sides of the shaft 85 which is journalled in bearings 84. The shaft 85 is wound with a spring 87, which is fixed at one end to the shaft 85 and at the other end to the back side of the base part so that the bent ends 88 of the lever 86 may be projected through the openings 82, while in the case of a larger record (12 inch) having to be fetched the other bent ends 89 of the lever may be projected through the openings 83 as the result of the end 88 being pressed against said record face. In that part of the curved part 78 which lies in the grooved support 80 is provided a slot 90 in which a sliding block 91 is supported by a spindle 81 and is pressed by a spring 92.

When the playing of the double-sided record has been completely finished and the driving shaft 39 is brought into rotation, as stated above, the record-turning-over-and-removing device 5 may be raised up through the engagement of the lever 68 with the cam disc A and in succession the record-fetching-and-putting-on device also may be raised up about the spindle 81 through the engagement of the curved part 78 with the point 10 IC of the cam disc C (refer to Figs. 2 and 6), whereupon said device presses the lower ends 15 of the unplayed records hanging on the rod 2. Then the device is driven to descend slightly when engaging the recess 2C of the cam disc C and in succession upon engagement of the curved 20 part 78 near the angle thereof with the elongated point 3C of said cam disc the device is pushed upwardly to such an extent, that the first record can be removed over the curved end of the rod 4. 25 The movements of the device are accomplished while the spring 92 is compressed in the slot 90 against the block 91 mounted on the spindle 81, and the device is guided by the block 91 in co-operation with the slot 90. In this way, the first 30 record, if it is a 10 inch one, may be supported on the bent ends 88 of the lever 86 and at the same time may fall down upon the arc-formed part by the action of the spring 5, whereupon the device may be gradually let fall down to put the record thus fetched upon the turn table. If the first 35 record is 12 inches in diameter, it is supported on the other bent ends 89 which will be projected through the openings 83 as the result of the bent ends 88 being pressed against the surface of the record.

Mechanism for controlling the position of the pick-up (refer to Figs. 7 and 8)

The device for controlling the pick-up so as to make the needle correctly position on the starting point of the sound groove, is composed of a lever 94 having upright rod 93 at one end and connected at other end to the lever 95 under the supporting plate 1. The free end of said lever 95 is positioned in a U-shape member fixed to the end of the lever 97 which has a pin 96 at the other end and is pivoted at the back side of the plate 1. The pin 96 is adapted to engage with the lever 31 in case of need. On both sides of the lever 95 are arranged the stops 99. After a record has been turned over and put on the turn table (condition as shown in drawings) or a new record has been fetched and put on the turn table, the lateral projection 35 of the shaft 40 may be driven to fall in the recess 40 of the tray-form cam disc 41 rotating together with the shaft 39 and in consequence the rollers 31 of the ring 36 is caused to travel on the tray-form cam disc 33 towards the recess 38. By this movement the supporting rod 29, then the pick-up 45 28 may be driven to move towards the record in accordance with the lever 31 moving through the friction against the ring 36. On the way of the movement of the lever 31 it engages with the pin 96 to turn the latter in the direction shown by arrow in Fig. 7, whereby the upright rod 93 also moves in the direction shown by arrow until it comes into contact with the periphery of the record, if it is a 12 inch one, so that the movement 50 of the pick-up stops. However, when the lateral projection 35 and the rollers 31 have completely fallen in the recess 40 and 38 respectively, the lever 31 descends to get free from the engagement with the pin 96, and in consequence the needle 100 comes into contact with

the starting point of the sound groove and at the same time the roller 103 of the switch 102 fits in the recess 101 of the disc 101 fixed to the end of the driving shaft 39. In this way the opening of the switch 102 is followed by the stoppage of the whole mechanisms. The turn table, however, is always rotated by its own motor, so that the playing of the record is to be started simultaneously with the stopping of the running of the motor 27. The controlling means is adjusted for a smaller record (10 inch) in such a manner that the needle comes into contact with the starting point of the sound groove when the movement of the lever 95 is prevented by the stop 99. From what is mentioned above it should be noted that the relation between the pick-up and the upright rod 93 or lever 95 and stop 99 must be predetermined in the manufacture of the machine to serve the aforesaid purpose.

As already referred to, the pick-up, after the completion of the playing of a record is followed by the close of the starting switch, may be separated from the record and carried away outside the record. On the way of this movement the pin 96 of the lever 97 is to be pushed back by the lever 31 to get free from the latter. A spring 104 is arranged under the supporting plate 1 to make the pin 96 turn back slightly to the position at which the latter is capable of engaging with the lever 31 in the next stage.

What has been stated hereinbefore relates to the action of the machine in the case of its being adapted for the double-sided record.

If the machine is desired to be used for the single-sided record it is sufficient merely to turn the control handle 71 till it points the mark (0) on the scale. From this operation may result the displacement of the cam group towards left in Fig. 5. Such displacement being realized through the arm 76, link 75 and lever 74, it 40 brings about the result that the cam disc A', B' and C' is brought into connection with the lever 68, 67 and the curved part 78 of the record-fetching device respectively.

In view of both points 1A' and 2A' of the cam disc A' being the equal distance from the center and the same distance from the center as the point 1A of the cam disc A, each record played may be suspended on the cross rod 1 every time the record-turning-over-and-removing device 50 may be raised up by the cam disc A'. The cam disc B' is cut off by the part corresponding to that containing the cam face 4B of the cam disc B, so that the record-holding member 48 may be driven to hold the record whenever either the point 1B' or 3B' of the cam disc B' engages with the lever 67, and to separate the record every time that either the point 2B' or 4B' leaves the lever 67, that is to say, the record-turning-over-and-removing device may be raised up. The 60 cam disc C' is composed of two parts, each of them being of the same form as the cam disc C, so that the record-fetching-and-putting-on device may be raised up on the engagement thereof with the point 1C' or 4C' of the cam disc C' and is driven to fetch the record on the point 3C' or 6C' every time the record-turning-over-and-removing device may be raised up.

The other mechanisms operate in the same manner as in the case of the double-sided record being played.

In order to stop or start each mechanism, if necessary, the motor 27 may be preferably connected to any other hand switch (not shown).

Having now particularly described and ascer-

tained the nature of my invention and in what manner the same is to be performed, I declare what I claim is:

1. In a device, to automatically change records on a phonograph turn table, the combination of a supporting plate, an upright post on said supporting plate, a cross piece projecting horizontally from said post to carry a plurality of disc records, a hook on the free end of said cross piece to hold the records on said cross piece, a disc, slidably mounted on said cross piece, a spring wound on the latter to press said disc resiliently towards said hook, and means to release one record from said hook and place it on the turn table, said means comprising a double armed lever having a slot in its mid portion, a spring pressed block slidably arranged in said slot, a trunnion supported on said table and projecting through said block and a cam below said supporting plate to control said lever, one arm of the latter projecting downwardly through an opening in the supporting plate and being crescent shaped to cooperate with said cam, the other arm having a base part and curved legs partly surrounding the turn table, said base part being provided with openings, two U-shaped levers pivoted to the lower side of said base part with their end portions opposite said openings and a spring to normally project the inner end portions of said levers through two of said openings.
2. In a device to automatically change records on a phonograph turn table, thereby taking off and replacing the pick up, the combination of a

supporting plate, a bearing on said plate to movably support the pick up, an upright guide rod connected to the pick up projecting downwardly through a curved slot in said supporting plate, a horizontal arm connected adjacent one of its ends to the lower portion of said guide rod, the other end of said arm forming a bearing, a frame depending from said supporting plate, a supporting disc fixed to the lower part of said frame, a vertical shaft projecting through said frame, said supporting disc and said bearing, the latter being loosely mounted on said shaft, a ring arranged on said shaft between said disc and said bearing in frictional contact with the latter, said ring being axially slidable with respect to said shaft and having at opposite sides thereof rollers adapted to roll on said disc and to rest in recesses provided at opposite sides of the latter, and cam controlled means to oscillate said shaft, thereby elevating and tilting said ring, bearing and arm, guide rod and the pick up.

3. A device, as claimed in claim 2, including further means to control the starting position of the pick up, said means comprising a link assembly adapted to be driven by said horizontal arm, said link assembly having an upwardly projecting pin on one side adapted to engage the rim of the record and on the other side a downwardly projecting finger retaining said elevated arm and thereby the pick up in the position in which the latter is situated above the first of the sound grooves.

TAIJI UEMURA.
